UNITED STATES PATENT OFFICE

131,642

DESIGN FOR A DRESS ENSEMBLE

William Slein, Philadelphia, Pa.

Application November 27, 1941, Serial No. 104,351

Term of patent 3½ years

To all whom it may concern:

Be it known that I, William Slein, a citizen of the United States and a resident of Philadelphia, county of Philadelphia, State of Pennsylvania, have invented a new, original, and ornamental Design for a Dress Ensemble, of which the following is a specification, reference being had to the accompanying drawing, forming a part thereof, wherein,

The characteristic feature of my design resides in the combination on the ensemble disclosed of the specific embroidered trim arranged on the jacket front and dress neckline in the manner and position shown.

I claim:

The ornamental design for a dress ensemble, as shown and described.

WILLIAM SLEPIN.
